UNITED STATES PATENT OFFICE.

SAMUEL S. STALEY AND MARK W. COLLET, OF PHILADELPHIA, PENNSYLVANIA.

AIR-PREHEATER FOR EXPLOSIVE-ENGINES.

1,387,328.

Specification of Letters Patent.

Patented Aug. 9, 1921.

Application filed January 7, 1918. Serial No. 210,628.

To all whom it may concern:

Be it known that we, SAMUEL S. STALEY and MARK W. COLLET, citizens of the United States, and residents of the city and county 5 of Philadelphia and State of Pennsylvania, have invented a new and useful Improvement in Air-Preheaters for Explosive-Engines, of which the following is a specification.

10 The present device belongs to the class where the kerosene or other heavy oil is heated enough for use in internal explosion engines by heating the air that enters the carburetor sufficiently to vaporize the oil 15 drawn into the mixing chamber of the latter. It has been recognized for some time that this pre-heating of the air was the best way of utilizing the heavier oils in internal explosion engines, but difficulty has been experienced in procuring a sufficient quantity 20 of air of the temperature required to heat the charge before its entrance into the cylinder to a temperature sufficient, in conjunction with the compression, to insure an explosion. The present device is aimed to furnish heated air in adequate quantity to supply the gaseous mixture in proper proportions before going into the cylinder.

Figure 1 is a plan view of the device. 30 Fig. 2 is a vertical section on the line 2—2 of Fig. 1. Fig. 3 is a section on the line 3—3 of Fig. 2. Fig. 4 is a section on the line 4—4 of Fig. 2. Fig. 5 is a bottom view of the device with the heater removed. Fig. 35 6 is an interior view of a portion of the outer wall of the chimney. Fig. 7 is a view of a part of the top of the device looking from below. Fig. 8 is a view of a portion of the bottom of the air heating chamber.

40 The casing 1 surrounds an air heating chamber and is spaced somewhat from it and below it forms a fire box. The lining 2 preferably of asbestos or similar material lies against the inside of the casing. The 45 bottom plate 27 incloses the casing at the bottom and has a sufficiently large opening to admit the burner 38 of a lamp. The chimney 35 has the outer wall (which is shown as the casing 1, of the device,) set 50 so as to leave a narrow space between it and the wall 23 of the air chamber which chamber is closed completely at the bottom by the diaphragm 28, which diaphragm is also of a heat conducting and radiating material. The cover 10 incloses the top of the 55 air heating chamber completely except for

the air inlets 14, 14. The diaphragm 28 is secured to the casing by the fingers 6 and to the wall 23 of the air heating chamber by the lugs 9, and the cover 10 is secured 60 to the casing by the fingers 11 and to the wall 23 of the air heating chamber by the lugs 12.

The air heating chamber is provided also with the pipe 7, that extends nearly to the 65 bottom of the chamber and is surrounded by the non-conducting covering 29. The pipe 7 passes through and extends above the cover 10 and in practice is secured to it by the nuts 8 and 26 above and below this cover 70 10 respectively. The fingers 11 extend to the casing 1 and are secured to it, and the lugs 12, 12, are secured to the wall 23 of the air heating chamber. The air heating chamber is provided also with the baffles 75 30, 31 of a heat conducting and radiating material. The baffles 30, are in contact with the wall 23 and spaced slidably from the pipe 7, and the partitions 31, fit closely the cover of the pipe 7 and are spaced from 80 the walls 23. The rods 15 and 16 pass from top to bottom of the air heating chamber and through the baffles 30 and 31. The rods 15, in practice, pass completely through the heating chamber and fire box and are conveniently held in place by their heads and the nuts 21 and 25. The rods 16 preferably terminate at the diaphragm 28 and are similarly secured to it by the nuts 20. The baffles are spaced by the washers 19, 19. 85 We have found the construction described above of great practical value because the heat from the fire-box is carried up by means of the rods 15 and 16 and the washers 19 to the baffles 30 and 31, and the washers 90 95 cause a much better conducting and radiation of the heat than a straight piece of pipe.

The wall 23 and the wall 1 form a chimney 35 and the heated air in the chimney 100 keeps the walls 23 continually hot, especially if the insulation 2 is sufficient to prevent it from being chilled.

The air to be heated is drawn into the heating chamber through the holes 14, 14, 105 and passes over the radiating baffles 30 and 31 downward (being repeatedly brought into contact with the heated wall 23 until it reaches the highly heated diaphragm 28, along which it passes to the mouth of the 110 pipe 7). It then passes through the latter out of the heater.

The velocity of the air is much greater near the pipe 7 where it is only heated by contact with the baffles 30 and 31 than near the heated wall 23, and moves most slowly 5 between the baffles 30 and 31 when nearest the wall. It can be made to pass in a very thin layer between the outer edge of the baffle 31 and the wall 23 and yet will pass slowly between them.

10 The importance of a large supply of air heated to a considerable extent is apparent when it is borne in mind that the best results are obtained in hydro-carbon internal explosion engines when the explosive mixture 15 is presented to the cylinder with the hydro-carbon in gaseous form. If the hydro-carbon is heavy it will less likely assume this form and more likely to be presented to the cylinder in a finely comminuted condition mixed with the air but still 20 liquid. By supplying the heated air in a large quantity and at a high temperature even the heavier oils such as kerosene or even fuel oil will be presented to the cylinder 25 in a gaseous form so that the compression will act upon a fuel ready to explode directly. We believe that up to the present time while many forms of pre-heaters have 30 been attempted, none of them have secured this result because of the small amount of 35 heating surface presented to the air in its passage to the carbureter and also that in none of them the air has been conducted to the carbureter in a comparatively thin flow over the heating surfaces. As is well known, 40 air cannot be heated by conduction and only with much difficulty by radiation but very readily by convection and it is by the application of the above principles that we believe we have made a thoroughly practical device.

We claim:

1. In an air preheater for internal combustion engines, an air heating chamber, a fire box, and its chimney, said firebox and chimney together inclosing the air heating chamber at the bottom and the sides, the walls between the firebox and the air heating chamber and the walls between the chimney and the air heating chamber being of heat conducting material, a series of baffles in the air heating chamber, each alternate baffle being slightly spaced from, and fitting snugly to the wall separating the air chamber from the chimney, a draw off pipe for the heated air, leading from the air heating chamber to the outside of the heater, and having its intake mouth near the wall between the air chamber and the firebox.

2. In an air preheater for internal combustion engines, an air heating chamber, a firebox and its chimney, said fire box and

chimney together inclosing the air heating chamber at the bottom and sides the walls 65 between the fire box and the air heating chamber and the walls between the chimney and the air heating chamber being of heat conducting materials, a series of baffles in the air heating chamber each alternate baffle 70 fitting snugly to and being spaced slightly from the wall separating the air heating chamber from the chimney, an air outlet pipe leading from the interior of the air chamber to the outside of the heater, having 75 its intake mouth near the wall between the fire box and the air heating chamber, and studs of a heat conducting material projecting 80 into the fire box and extending through the air heating chamber.

3. In an air preheater for internal combustion engines an air heating chamber, a fire box and its chimney, together inclosing the air heating chamber at the bottom and the sides, the walls between the fire box and 85 the air heating chamber, and between the chimney and the air heating chamber being of heat conducting material, baffles in the air heating chamber, each alternate baffle fitting snugly to and being slightly spaced 90 from the wall between the fire box and the air heating chamber, studs of a heat conducting material projecting into the fire box and extending through the air heating chamber, and washers placed around the 95 said studs, the washers and the baffles being of heat conducting material, and a hot air outlet pipe, leading from the interior of the fire box to the outside of the heater, and having its intake mouth near the wall between the air chamber and the fire box.

4. In an air preheater for internal combustion engines, an air heating chamber, a fire box and its chimney together inclosing the air heating chamber at the bottom and 105 the sides, the walls between the air heating chamber and the chimney and between the air heating chamber and the fire box, being of a heat conducting and heat radiating material, a series of baffles extending crosswise 110 of the air heating chamber, certain of these baffles guiding the air toward the center of the air heating chamber, and others of these baffles, guiding the air in the air heating chamber, outward toward the wall between the air heating chamber and the chimney, and an air outlet pipe leading from the 115 interior of the heater to the outside thereof, having its intake mouth toward the bottom of the air heating chamber.

In witness whereof we have hereto set our signatures.

SAMUEL S. STALEY.
MARK W. COLLET.
